SHOE JACK

Dionisie I. Salcaian, Canton, Ohio

Application May 3, 1932. Serial No. 608,893

7 Claims. (Cl. 12—123)

The invention relates to jacks employed in making or repairing shoes and embodies improvements enabling a cobbler to make, resole or repair shoes with greater facility, speed and efficiency than has heretofore been possible with the jacks in common use.

Prior types of jacks have comprised a rigid upright post mounting the shoe form in inverted position. It is a requirement of a shoe jack that it be sufficiently rigid to withstand the hammer blows imparted to the shoe on the form, but with the old type of shoe jack, it becomes awkward to work on the edge of the sole or on certain other parts of the shoe because the shoe form is always rigidly maintained in upright position. It is therefore desirable to swing the shoe form to an inclined position in a manner to render all parts more conveniently accessible, and at the same time provide for selectively rigidly maintaining the shoe form in a vertically upright position.

Certain fabricating and repairing operations to be performed upon the shoe are very awkward and unsatisfactory when the shoe is rigidly maintained in a vertically upright inverted position, so that the cobbler finds it expedient to remove the shoe from the jack and hold it manually several times during the fabricating or repairing procedure. Consequently, considerable time is lost, and moreover, it is extremely difficult while holding the shoe in this manner to perform work of the highest character.

Accordingly, it is an object of the present invention to provide a shoe jack, which will enable the satisfactory performance of substantially all of the necessary repairing operations upon the shoe without removing it from the shoe jack.

Another object is to provide a shoe jack which will solidly and rigidly mount the shoe in position for hammering upon the sole, and at the same time permit swinging movement of the upper portion of the jack to an inclined position so as to render certain parts of the shoe more accessible.

Another object is to provide a shoe jack having an upright supporting post capable of axial rotary movement relative to its base.

A further object is to provide a jack having ratchet means permitting axial rotary movement of the shoe form in the supporting post.

And finally, it is an object of the present invention to incorporate all of the foregoing advantageous features in a simple, compact and inexpensive construction which is commercially practicable.

These and other objects are attained by the improvements comprising the present invention, which may be stated in general terms as including a base, an upright supporting post rotatably mounted in the base, means for detachably securing said post in a plurality of axial positions in the base, a shoe form mounting member pivotally mounted upon the upper end of the supporting post for swinging movement relative thereto, means for selectively maintaining said mounting member in upright or inclined position, and means for releasably securing a shoe form in a plurality of axial positions in said mounting member.

In the drawing forming part hereof

Figure 1 is an elevational view of the improved jack, showing the base partially in section;

Fig. 2 is a fragmentary view similar to Fig. 1, showing the mounting member in an inclined position, and a part of the supporting post being broken away;

Fig. 3 is a plan sectional view taken on line 3—3, Fig. 1;

Fig. 4 is a top plan view of the jack, showing various axial positions of the shoe form; and

Fig. 5 is a fragmentary sectional view as on line 5—5, Fig. 4.

Similar numerals refer to similar parts throughout the several views.

The improved shoe jack preferably includes a base 10, having a depending flange 11 for resting upon the floor or other support, and an upstanding tubular flange portion 12; and the base 10 is preferably provided with holes 13 for securing the same to the floor.

A supporting post 14 is rotatably mounted in the base 10, and may be provided at its lower end with a cylindrical portion 15, which is closely swivelled in the flange portion 12 for maintaining the post 14 in a vertically upright position. The portion 15 is preferably provided with an angular flange 16 normally spaced below the central portion of the base 10 for limiting upward movement of the supporting post 14.

The upper edge of the flange portion 12 is preferably provided with a plurality of circumferentially spaced notches 17, and a pin 18 extends through the post 14 for engaging in diametrically opposite notches 17 for detachably securing the post in a plurality of axial positions in the base.

The upper end of the supporting post 14 is preferably tubular, and is provided with a pair

of diametrically opposite upwardly extending ears 19, the upper edge 20 of each ear being preferably flat. Between the ears 19 the upper edge of the post curves downwardly to form diametrically opposite stop shoulders 21 for a purpose to be hereinafter described.

A shoe form mounting member 22 is preferably provided with a rounded lower end 23 fitting closely within the tubular upper end of the post 14, and the member 22 may be provided adjacent its lower end with a circumferential recessed portion 24 forming the peripheral shoulder 25. The mounting member 22 preferably tapers inwardly from the shoulder 25 to its upper end.

Means for pivotally mounting the mounting member 22 in the post 14 for swinging movement relative thereto in opposite directions, may include a pin 26 journaled in a slot 27 formed in the central portion of the lower end of the mounting member, and projecting through the ears 19, forming a slot and pin connection between the mounting member and the post.

The shoulder 25 is provided with diametrically opposite flat portions 28, which are adapted to engage the flat edge portions 29 of the post when the mounting member is in upright position and the pin 26 is at the top of slot 27. Since the rounded end 23 of member 22 fits closely within the upper end of post 14, the mounting member 22 will be rigidly maintained in upright position by the engagement of edge portions 20 with shoulder portions 28.

By raising the mounting member 22 to the position shown in dot-dash lines in Fig. 2, with the pin 26 at the bottom of slot 27, the member 22 may be swung about the pin 26 as a pivot, to the right as shown in Fig. 2, or to the left until the recessed portion 24 is engaged by one of the stop shoulders 21 for maintaining the mounting member in inclined position.

The upper end of mounting member 22 is preferably tubular, as indicated at 29, and the shoe form 30 is preferably provided with a substantially cylindrical portion 31 adapted to fit within the tubular portion 29. The cylindrical portion 31 may be provided with a peripheral groove 32, and preferably has ratchet teeth formed on its lower end as shown at 33.

Ratchet pawls 34 are slidably inserted through suitable apertures in the tubular portion 29 of member 22 for engaging the ratchet teeth 33 at diametrically opposite portions.

Means for releasably securing the shoe form 30 in a plurality of axial positions in the member 22 may include a curved, substantially semi-cylindrical spring member 35, adapted to snap fit around the upper end of the member 22. The spring member 35 is preferably provided with an upwardly extending ear 36, to which is secured a stud 37. The stud 37 is adapted to slidably extend through a suitable aperture in the tubular portion 29 of member 22 and engage the groove 32 for rotatably supporting the shoe form 30.

The spring member 35 includes curved arms 38 extending in opposite directions from the ear 36, and the arms 38 are adapted to fit around member 22 and over pawls 34 for resiliently holding said pawls inwardly against the ratchet teeth 33. The ratchet teeth 33 are preferably slightly tapered as shown in Fig. 5, to facilitate insertion into mesh with the pawls 34.

It will be seen that shoe forms having different foot sizes or shapes may be readily inserted into

or removed from the tubular portion 29 of the mounting member because of the yielding resistance offered by the spring pressed stud 37. The shoe form is releasably secured in any of a plurality of axial positions in the mounting member, such as shown in Fig. 4, by means of the pawls 34 and ratchet teeth 33. The spring 35 presses the pawls against the ratchet teeth to provide sufficient resistance to twisting or rotary movement of the form for all practical purposes, but permits rotary movement of the form from one position to another by a quick manual twist upon the form.

In the operation of the improved jack, when a shoe is mounted upon the form with the mounting member 22 in upright position, as shown in Fig. 1, the operator may pound at will upon the shoe and the mounting member will be rigidly maintained in its upright position in the manner previously described. When it is desired to render some portion of the shoe more easily accessible without removing it from the form, the mounting member may be quickly and easily swung to the right or left to assume an inclined position, as previously described in connection with Fig. 2. In this inclined position, the form may be rotated to a plurality of axial positions in the mounting member, and the whole jack may be axially rotated in the base to a plurality of positions by raising the post 14 and engaging the pin 18 in a different pair of notches 17.

The result of this combination of adjustments is to make it practicable for the cobbler to rapidly and efficiently perform substantially all of the required shoe making and repairing operations upon a shoe without removing it from the form.

The simple and compact construction of the improved jack makes it extremely inexpensive to manufacture, and the above described advantages of operation result in a substantial saving of time and effort, without detracting from the high character of the work performed.

I claim:

1. A shoe jack and the like including a base, an upright supporting post rotatably mounted in the base, means for detachably securing said supporting post in a plurality of axial positions relative to the base, a shoe form mounting member pivotally mounted in the supporting post, and means for selectively maintaining the mounting member in an upright or in oppositely inclined positions.

2. A shoe jack and the like including an upright supporting post, a shoe form mounting member, and a shoe form, means pivotally mounting said mounting member in the supporting post, means for selectively maintaining the mounting member in an upright or in oppositely inclined positions, and spring-pressed means for releasably securing the shoe form in a plurality of axial positions in the mounting member.

3. A shoe jack and the like including an upright supporting post having a tubular upper end, a shoe form mounting member pivotally mounted in the upper end of said post for swinging in opposite directions and having a recessed portion forming a shoulder, the upper edge of the post having a flat portion adapted to engage said shoulder for maintaining the mounting member in upright position, and another portion of the upper edge of the post being adapted to engage the recessed portion for maintaining the mounting member in oppositely inclined positions.

4. A shoe jack and the like including an upright supporting post having a tubular upper end, a shoe form, a shoe form mounting member pivotally mounted in the upper end of the post for swinging movement relative thereto in opposite directions, said mounting member being provided with a shoulder, the upper edge of said post having diametrically opposite upwardly extending ears adapted to engage said shoulder for maintaining the mounting member in upright position, and means for releasably securing the shoe form in the mounting member. 10
5. A shoe jack and the like including a base, an upright supporting post rotatably mounted in the base and having a tubular upper end, means for detachably securing said post in a plurality of axial positions in said base, a shoe form mounting member pivotally mounted in the upper end of said tubular post for swinging in opposite directions and having a recessed portion forming a shoulder, the upper edge of the post having a flat portion adapted to engage said shoulder for maintaining the mounting member in upright position, and other diametrically opposite portions of said upper edge being adapted to engage the recessed portion for maintaining the mounting member in oppositely inclined positions. 15
6. A shoe jack and the like including an upright supporting post having a shoulder at its upper end, and a shoe form mounting member having a slot and pin connection with the upper end of said post and adapted normally to be maintained in an upright position by engagement with said shoulder, said slot and pin connection permitting raising of the mounting member to disengage it from said shoulder for swinging the mounting member in opposite directions. 20
7. A shoe jack and the like including an upright supporting post having a shoulder at its upper end, a shoe form mounting member having a slot and pin connection with the upper end of said post and adapted normally to be maintained in an upright position by engagement with said shoulder, said slot and pin connection permitting raising of the mounting member to disengage it from said shoulder for swinging the mounting member in opposite directions, and means for maintaining the mounting member in oppositely inclined positions. 25
